UNITED STATES PATENT OFFICE

CLYDE B. FAVERTY, OF HAMMOND, INDIANA, ASSIGNOR TO RAILWAY LOCOMOTOR COMPANY, OF CHICAGO, ILLINOIS, A CORPORATION OF ILLINOIS

DESIGN FOR A COMBINATION RAILWAY CAR AND STEAM LOCOMOTIVE

Application filed September 3, 1929. Serial No. 32,644. Term of patent 7 years.

To all whom it may concern:

Be it known that I, CLYDE B. FAVERTY, a citizen of the United States, residing at Hammond, in the county of Lake and State of Indiana, whose post-office address is 11 Ruth Street, Hammond, Indiana, have invented a new, original, and ornamental Design for a Combination Railway Car and Steam Locomotive, of which the following is a specification, reference being had to the accompanying drawing, forming part thereof.

Fig. 1 is a perspective view of the design showing the front and one side.

Fig. 2 is an elevational view showing the opposite side but with trucks removed.

Fig. 3 is a full front elevational view.

I claim:

The ornamental design for a combination railway car and steam locomotive as shown.

CLYDE B. FAVERTY.
